UNITED STATES PATENT OFFICE.

WILBUR T. CLARK, OF CLEVELAND, OHIO, ASSIGNOR OF ONE-HALF TO PATRICK J. MORAN, OF EAST CLEVELAND, OHIO.

GAS-BURNER.

1,397,501.

Specification of Letters Patent.

Patented Nov. 22, 1921.

Application filed September 17, 1920. Serial No. 410,903.

To all whom it may concern:

Be it known that I, WILBUR T. CLARK, a citizen of the United States, resident of Cleveland, county of Cuyahoga, and State 5 of Ohio, have invented new and useful Improvements in Gas-Burners, of which the following is a specification, the principle of the invention being herein explained and the best mode in which I have contemplated 10 applying that principle, so as to distinguish it from other inventions.

My invention relates to gas burners. Particularly, the invention relates to a new and improved combination of means for mixing 15 air and gas for use in connection with blast furnace operations, boiler operations, etc. The object of the invention is to provide a combination of such means in which economically there will be provided a well- 20 mixed fuel furnishing hot combustion.

The annexed drawings and the following description set forth in detail certain means embodying my invention, the disclosed means, however, constituting but one of the 25 various mechanical forms in which the principle of the invention may be applied.

In said annexed drawings:

Figure 1 represents a central vertical longitudinal section of a gas burner embodying my improved means, a suggestion of the ordinary blast furnace stove being also shown;

Fig. 2 represents a fragmentary elevation of a stove door and its support, the door 35 being shown in closed position;

Fig. 3 represents a partial side elevation and a partial central vertical longitudinal section of the elements illustrated in Fig. 1, showing the stove door in position and the 40 burner moved out from the stove;

Fig. 4 represents a front elevation of a pair of units embodying my invention, as applied in connection with boiler operation; and

Fig. 5 represents a fragmentary central vertical longitudinal section of one of the units shown in Fig. 4, taken in the plane indicated by the line V—V, in said figure.

In the annexed drawings, Figs. 1, 2 and 50 3, an exemplification of my improved gas burner is shown in relation to a blast furnace stove 1, an annular casing which surrounds and lies adjacent to the stove door opening, and to which is fitted the usual cover, as

hereinafter explained, being indicated by the 55 ordinal 2. As is well known in blast furnace practice, there is provided a gas conduit 3 controlled by a valve 3². I sub-divide this conduit 3 before the same discharges into the combustion chamber 6 of the stove 60 1 and make two conduits thereof, a central main cylindrical conduit 8 and a surrounding annular conduit 4. This latter conduit 4, or by-pass from the conduit 3 to the chamber 6, is formed by a nozzle 9 and is controlled 65 in the manner hereinafter described in detail. The central main conduit 8 is formed by a nozzle 8', including an elbow 8² mounted in a nozzle 12, and is controlled by a valve 8³. The nozzle 12 forms an annular conduit 5 surrounding the conduit 8, controlled by a suitable valve 5², and furnishing air to the combustion chamber 6. This air conduit 5 is disposed intermediately 70 of the gas conduit 8 and the gas by-pass 4. 75 These conduits 4, 5 and 8 discharge into the combustion chamber 6 through a fitting 10 which, in the form of device shown, is an extension of the nozzle 9 forming the annular gas passage 4, and has a central restricted portion 10 forming, in effect, a venturi, and producing the usual increased velocity 80 of a venturi. The result of this construction will be hereinafter described in detail. Mounted exteriorly of the venturi connection 10 is a ring 11 which is adjustable upon the fitting 10 inwardly and outwardly of the combustion chamber 6 to control an outer auxiliary air inlet 7 discharging into the 85 combustion chamber 6 exteriorly of the venturi connection 10. Also, the nozzle 12 forming the air passage 5 is adjustable toward and from the venturi connection 10 to control the opening 16, through which the gas 90 from the by-pass 4 passes into the venturi 95 10. This adjustment is secured by means of the collar 13 secured exteriorly of the nozzle 12 and adjustable longitudinally of the nozzle 9 by means of the elongated slots 14 formed in the nozzle 9, the collar 13 being 100 secured to the nozzle 9 by means of the bolts 15, intersecting said slots 14, as plainly shown in Fig. 1.

The venturi connection is in two separable parts and consists of a stationary casting 10² secured to the stove 1 and a movable coöperating casting 10³ mounted upon the nozzle 9. The increased velocity induced by 105

the restricted portion 10' of the venturi creates a suction which pulls in more air through the passage 5. In speeding up the velocity of the gas a negative pressure is created which induces an increased volume of air. The enlargement 102 of the venturi slows up the velocity and induces a swirling motion which creates a good mix between the gas and air. An outer lip 10⁴ upon the casting 10² also aids in creating a swirling between the gas and air, this lip being of less diameter than middle portion of the casting 10². The construction also creates a negative pressure inducing additional air through the 15 exterior auxiliary air inlet 7. This outer venturi effect is caused by the restricted opening formed between the enlargement 10² of the venturi 10 and the stove casing. This outer venturi also results in a still better 20 mixture between the gas and air.

Whenever it is desired to discontinue the furnishing of gas and air to the stove 1, the nozzles 9 and 12, including the movable part of the fitting 10, and the pipe 8' are moved 25 back away from the door of the stove 1 in the manner hereinafter described, and the cover 17 is swung into place. This cover 17 is carried by the hanger 18, in turn carried by suitable trolley wheels, and also supporting the spider 19, of the design plainly shown in Fig. 2, which is adapted to inclose the bolts 20 and to receive the hinge bolt 21. The means for moving the nozzles 9 and 12 30 relatively to the stove 1 are provided by the hand wheel 22 rotatably secured to a shaft 23, to which shaft is secured a pinion 24 adapted to engage with a rack 25 suitably supported. The base upon which the rack 25 is mounted is adapted to cover the opening 40 3' of the gas passage 3 when the nozzles are moved back from the stove, as plainly shown in Fig. 3. This construction for moving the nozzles inwardly and outwardly of the stove 45 is well known to those versed in the art. The line of separation between the two venturi castings 10² and 10³ is so designed that they form a smooth surface when the burner is in its inner working position.

Referring to Figs. 4 and 5, there is therein 50 suggested by the ordinal 27 a boiler having a combustion chamber 26. These figures illustrate the application of my new and improved gas burner to the operation of such boiler. In this application, the gas passage 55 3 is not sub-divided, so that the gas is furnished to the chamber 26 by means of only one conduit 4', the latter being controlled by the valve 29. In this application, the gas burner is permanently fixed and the venturi 60 10⁵ is an integral extension of the gas nozzle 9'. Air is furnished interiorly of the gas conduit 4' through the conduit 5', and the latter is controlled by a damper 28 having apertures 28' adapted to register varying 65 amounts with the openings of the pipe 5', or

to close said openings completely. Externally of the forward venturi extension 10⁵ of the gas nozzle 9' is formed an auxiliary air inlet 7' controlled by the adjustable collar 11', all as plainly shown in Fig. 5. I have shown two units of my improved gas burner supplied to the boiler 27, and it will be noted that a plurality of air pipes 5' are provided for each unit, there being six of these pipes, in the form of device shown, contained within each gas nozzle 9'.

Inasmuch as the device disclosed herein is of quite general application, it is to be understood that the term "furnace" as used in the claims is intended to refer generically to any structure or mechanism having a combustion chamber adapted to be heated by burning gas therein.

What I claim is:

1. In a gas burner, the combination with 85 a furnace having a combustion chamber; of a nozzle comprising concentric tubular conduits forming air and gas passages, the outer conduit extending beyond the inner and having a restricted discharge end; and 90 a tubular casting fixed to the furnace, having an outer restricted end adapted to make a smooth joint with the restricted discharge end of said nozzle and having an inner restricted discharge end, said nozzle being 95 movable toward and from the furnace.

2. In a gas burner, the combination with 100 a furnace having a combustion chamber; of an annular gas nozzle; means forming an air inlet interiorly of said nozzle; a tubular casting fixed to said nozzle and forming a continuation thereof; a tubular casting fixed to the furnace and adapted to make a smooth joint with the first mentioned casting, said 105 castings forming a venturi extension for the nozzle; and means forming an auxiliary air inlet to said chamber surrounding said venturi extension, the nozzle being movable toward and from the furnace.

3. In a gas burner, a gas nozzle comprising 110 an outer tubular casing and inner tubular conduits forming a central tubular passage and surrounding annular passages, said outer casing projecting beyond said inner tubular conduits and having a restricted discharge end; and means for admitting gas and air to alternate passages.

4. In a gas burner, a gas nozzle comprising 115 an outer tubular casing and inner tubular conduits forming a central tubular passage and surrounding annular passages, said outer casing having a double venturi extension beyond the discharge ends of said inner conduits, said extension having a restricted portion, an intermediate enlarged portion 120 and a restricted discharge orifice; and means for admitting air and gas to alternate passages.

5. In a gas burner, the combination with 130 a furnace having a combustion chamber; of

- 5 a gas nozzle comprising discharge extension having alternate enlarged and restricted portions and forming a mixing chamber; and air and gas inlet passages opening into said extension; and a converging air inlet passage into said combustion chamber surrounding said extension.
6. In a gas burner, the combination with a furnace having a combustion chamber; of 10 an annular gas nozzle; means forming an air inlet interiorly of said nozzle; a casting fixed to said nozzle and projecting forwardly thereof; a casting secured to the furnace and adapted to make a smooth joint with the 15 first mentioned casting, said castings forming a venturi extension for said nozzle; means forming an auxiliary air inlet to said chamber surrounding said venturi extension, the nozzle being movable toward and from 20 the furnace; and means secured to the stove and forming, in combination with the aforementioned furnace venturi-casting, a venturi through which the auxiliary air passes.
7. In a gas burner, the combination with 25 a furnace having a combustion chamber; of means forming a gas passage leading to said chamber; a by-pass from said passage to said chamber; means for controlling said by-pass; means furnishing air to said chamber 30 intermediately the gas streams issuing from said gas passage and said by-pass; a casting secured in said gas passages and said air-furnishing means and surrounding and extending forwardly of the same; a casting secured 35 to the furnace and adapted to make a smooth joint with the first mentioned casting, said castings forming a venturi connection intermediate the stove and the nozzle and inlet; and means forming an air inlet to said chamber 40 surrounding said venturi connection, the nozzle and inlet being movable toward and from the furnace.
8. In a gas burner, the combination with a furnace having a combustion chamber; of 45 means forming a gas passage leading to said chamber; a by-pass from said passage to said chamber; means for controlling said by-pass; and means furnishing air to said chamber intermediately the gas streams issuing 50 from said gas passage and said by-pass.
9. In a gas burner, the combination with a furnace having a combustion chamber; of means forming a gas passage leading to said chamber; a by-pass from said passage to said 55 chamber; means for controlling said by-pass; means furnishing air to said chamber intermediately the gas streams issuing from said gas passage and said by-pass; and means furnishing auxiliary air to said chamber exteriorly 60 of the aforesaid gas passage and by-pass.
10. In a gas burner, the combination with a furnace having a combustion chamber; of means forming a gas passage leading to said 65 chamber; a by-pass from said passage to said
- chamber; means for controlling said by-pass; means for controlling said gas passage intermediate said by-pass and said chamber; and means furnishing air to said chamber intermediately the gas streams issuing from said 70 gas passage and said by-pass.
11. In a gas burner, the combination with a furnace having a combustion chamber; of means forming a gas passage leading to said chamber; a by-pass from said passage to 75 said chamber and surrounding said passage; means for controlling said by-pass; means furnishing air to said chamber intermediately the gas streams issuing from said gas passage and said by-pass; and means fur- 80 nishing auxiliary air to said chamber exteriorly of said by-pass.
12. In a gas burner, the combination with a furnace, having a combustion chamber; of means forming a gas passage leading to 85 said chamber; a by-pass from said passage to said chamber and surrounding said passage; means for controlling said by-pass; means furnishing air to said chamber intermediately the gas streams issuing from 90 said gas passage and said by-pass; means furnishing auxiliary air to said chamber exteriorly of said by-pass; and means forming a venturi through which the auxiliary air 95 passes.
13. In a gas burner, the combination with a furnace having a combustion chamber; of means forming a gas passage leading to said chamber; a by-pass from said passage to said chamber and surrounding said passage; means for controlling said by-pass; means furnishing air to said chamber intermediately the gas streams issuing from 100 said gas passage and said by-pass; means for controlling said air-furnishing means; means 105 furnishing auxiliary air to said chamber exteriorly of said by-pass; and means for controlling said auxiliary air.
14. In a gas burner, the combination with a furnace having a combustion chamber; of means forming a gas passage leading to said chamber; a by-pass from said passage to said chamber and surrounding said passage; means for controlling said by-pass; means furnishing air to said chamber intermediately 110 the gas streams issuing from said gas passage and said by-pass, said by-pass being formed into a venturi projecting forwardly of said air-furnishing means, through which venturi the gas from the gas 115 passages, and said air, pass; and means furnishing auxiliary air to said chamber exteriorly of said venturi.
15. In a gas burner, the combination with a furnace having a combustion chamber; of a controllable gas passage leading to said chamber, said passage being subdivided into a central cylindrical conduit and a surrounding annular conduit; means for controlling said annular conduit; means form- 125 130

ing a controllable annular air conduit disposed intermediate said central gas conduit and said annular gas conduit; and means forming a controllable auxiliary air inlet to said chamber exteriorly of said annular gas conduit.

16. In a gas burner, the combination with a furnace having a combustion chamber; of a controllable gas passage leading to said chamber, said passage being subdivided into a central cylindrical conduit and a surrounding annular auxiliary conduit; means for controlling said auxiliary conduit; means forming a controllable annular air conduit disposed intermediate said central gas conduit and said annular gas conduit, the latter being formed into a venturi projecting forwardly of said air conduit, into which venturi the air conduit and the gas conduits discharge; and means forming a

controllable auxiliary air inlet to said chamber exteriorly of said venturi.

17. In a gas burner, the combination with a furnace having a combustion chamber; of a controllable gas passage leading to said chamber, said passage being subdivided into a central cylindrical conduit and a surrounding annular auxiliary conduit; means for controlling said central conduit; means for controlling said annular conduit; means for forming a controllable annular air inlet to said chamber exteriorly of said annular conduit.

Signed by me, this 7th day of September, 1920.

WILBUR T. CLARK.
